RADIO CLOCK

Marvin D. York, Marlow, Ky., assignor of one-half to Reuel O. Thomas and wife Flossie G. Thomas, Marlow, Ky.

Application April 6, 1938, Serial No. 200,508

7 Claims. (Cl. 200—39)

This invention relates to radio clocks and has for its principal object to provide in connection with a clock for use as an ordinary time piece, either as an external adjunct or built into the 5 radio cabinet, means in addition to and cooperative with the clock mechanism to take the place of the regular "on" and "off" switch of a radio for automatically rendering the radio operative or inoperative at a desired set time.

10 Another object is to utilize an ordinary alarm clark mechanism without material alteration therein in the adaptation of the radio switch operating and controlling means thereto.

15 A further object is to provide a mechanism which may be operated manually, at will, as well as automatically.

With these and other objects to be attained, the invention consists in the novel general structure and parts and combinations and arrangements of parts as hereinafter described and pointed out with particularity in the appended claims, reference being had to the accompanying drawings illustrating a practical adaptation of the invention, and in which—

25 Figure 1 is a front elevation of the clock case and the exposed parts of the structure;

Figure 2 is a right side elevation;

Figure 3 is a fragmentary vertical section, on an enlarged scale, through the clock case and 30 the interior mechanism;

Figure 4 is a vertical section taken at right angles to the section shown in Figure 3 illustrating details of the switch gear and the setting gears viewed from the rear;

35 Figure 5 is a fragmentary face view, on an enlarged scale, showing details of the clock dial face and dial of the switch setting mechanism, together with certain of the gears associated with the switch setting mechanism;

40 Figure 6 is a horizontal section showing portions of the winding mechanism and operating gearing for the switch controlling mechanism;

Figure 7 is a detail of the on and off controlling lever;

45 Figure 8 is a view showing the switch gear actuated to the "off" position;

Figure 9 is a fragmentary plan view and partial section showing the relation of the switch gear to the terminal contact elements of the on and 50 off circuit of the radio; and

Figure 10 is a detail view of the releasable latch and star wheel of the on and off switch controlling mechanism.

Referring now to the drawings the numeral 55 designates an outer casing containing the clock

mechanism and the radio switch operating and controlling mechanism to be hereinafter described, said casing having a back closure plate 16 on which is mounted two terminal posts 17, 18, which are suitably insulated from each other and from said plate 16 and have respectively attached thereto wires 19 and 20 which are extensions of the usual circuit wires that are connected to the regular on and off switch of a radio and in place of which the mechanism of the 10 present invention is substituted.

5 Mounted on the upper portion of a rear plate member 21 which is a part of the supporting frame of the clock mechanism to which the particular elements of the present invention are 15 adapted and applied, is a bracket 22 of suitable insulation material, said bracket having a pair of circuit terminal elements 23 attached thereto, said elements 23 being preferably in the form of resilient tongues or brushes extending in parallel 20 relation to each other and having opposed contact buttons 24 on their outer end portions and being provided at their inner ends with out-turned angular extensions 25 which are apertured for the reception of securing bolts 26, 27, which 25 latter, in addition to securing the elements 23 to the block 22, afford means of attachment for wires 28, 29, which are respectively connected to said terminal posts 17, 18.

30 Interposed between the two terminal tongue or brush elements 23 is a gear 30 having on its opposite sides a pair of annular insulation elements 31, which latter, as shown in Figure 7, are connected at four diametrically opposite points by necks 32 of insulation material, said 35 neck portions 32 extending through apertures provided therefor in the adjacent body portions of the gear and having bores therethrough whereby they are, in effect, insulating bushings in which are located electric conducting studs 33 having flat-faced circular head portions at their opposite ends which are countersunk into the faces of the said insulation rings 31. The opposed contact buttons 24 on said resilient terminal elements 23 bear normally against the opposite sides of the 40 gear 30, either upon the faces of the insulating rings 31 or the end faces of the studs 33, and whereby the operating circuit for the radio is either opened or closed through the wire connections 19, 20, 28 and 29, depending upon the 45 position of the gear 30 when the latter is brought to rest as will presently more fully appear.

46 Hingedly mounted on an upper shelf portion 34 of the front plate member 35 of the frame which supports the clock mechanism, is a sub- 50

stantially T-shaped lever 36 whose transverse head portion 37 extends equally on opposite sides of its pivot 38 and has a latch arm 39 pivotally attached thereto at one end, as at 40, and a similar latch arm 41 pivoted, as at 42, to its opposite end. Said arms 39 and 41 are connected by a spring 43 which normally urges them toward each other and respectively into contact with stop pins 44, 45 across which said arms 39 and 41 slide into and out of engaging relation to said gear 30 by rocking the lever 36 on its pivot 38.

The gear 30 is provided with a plurality of spokes 46, preferably four, as shown, connecting its hub and rim portions in diametrical alignment with the contact studs 33, and, in this connection, the pivotal arm 39 of the lever 36 is of such length that its outer end portion is moved into the path in which said spokes 46 travel when the gear 30 is rotated, so that in one position of the lever 36, as shown more clearly in Figure 7, said gear 30 is arrested in its rotative movement by the engagement of one of the spokes 46 with said arm 39. In the reverse position of the lever 36 the arm 39 is retracted so that its outer end portion is clear of the spokes 46, and said gear 30 would ordinarily be free to rotate, but it is provided with four radial lugs 47 which are disposed inwardly from the rim of the gear 30 in diametrical opposed relation to each other and staggered or alternately disposed annularly between said spokes 46, said lugs 47 being off-set laterally out of the plane of the spokes 46, and are engageable with the outer end portion of the arm 41 of said lever 36, which latter is relatively shorter than said arm 39, but moves into the path of said lugs 47 before the other arm 39 releases the engaged spoke 46, that is to say, one or the other of said arms 39 or 41 is at all times in engaging relation to said gear 30.

By the foregoing provision and arrangement of the pivotal arms 39, 40, and the wheel spokes 46 and lug members 47, the gear 30 is selectively stopped in its rotation by the manipulation of said lever 36 and the circuit through the members 23 and respective connecting wires to the radio is thereby closed and opened, at will.

The stem portion of said lever 36 is projected through a slot 48 in the front wall of the case 15 and provided at its outer end with a suitable knob 49, and, to indicate the proper circuit opening and closing positions of said lever 36, "off" and "on" legends are obviously indicated at opposite ends of said slot 48.

In the preferred embodiment of the invention as illustrated in the accompanying drawings, said gear 30 is a part of the conventional alarm mechanism of the clock and when released from engagement with either of the pivotal arms 39 and 41 of said lever member 36, is set in rotative motion by the timed release of said alarm mechanism, which latter will be now generally described.

As shown, the alarm mechanism comprises a main shaft 50 on which a winding gear 51 is loosely mounted rotatably but held against endwise movement, said gear being in cooperative circumferential engaging relation to a reciprocating rack bar 52 having a knob 53 on its outer end by which said bar is moved inwardly and outwardly, and by the engagement of its rack teeth with the gear 51 imparts an oscillatory movement to said gear. The gear having a pawl 53' yieldably held in engagement with a ratchet wheel 54 fixed on the shaft 50, said shaft is rotated in one

direction to wind a spring located in the barrel 55 about the shaft 50, as in the usual winding means of the alarm mechanism of a clock, said spring (not shown) being obviously attached to the barrel and shaft so that the latter is driven under the power of the reactive spring, in the usual manner when the alarm mechanism is released.

For the purposes of the present invention, shaft 50 is provided with a gear 56 which meshes with an intermediate gear 57, which latter in turn meshes with the gear 30 and effects the rotation of the latter upon the retraction of either the arm 39 or 41, as the case may be, and until said gear is arrested in its rotative movement by its engagement with the opposite pivotal arm as hereinbefore described.

To normally lock the shaft 50 against rotation, it is provided with a gear 58 which is fixed thereon to rotate therewith, said gear 58 meshing with a pinion 59 fixed on a shaft 60 and having a star wheel 61 fixed thereto and which is engaged by a dog 62 formed by tapering the down-turned rebent portion 63 at the upper end of a spring tongue 64 which is riveted to the outer face of the frame plate 35, as at 65, said portion 63 working through a slot in said plate 35 and said dog 62 being urged laterally out of the space between an adjacent pair of the pointed teeth of said star wheel 61 (see Figure 10), but is normally held in engagement with said star wheel 61 by the end engagement of a hub portion 66 of a gear 67 with a pin 68 fixed on a shaft 69, said hub and pinion being rotatable freely and with endwise movement on said shaft 69 and having an opposed hub portion 70 which bears against said spring member 64, so that, when said gear 70 is rotated in one direction on said shaft 69, the pin 68 rides out of a notch 71 in the end of said outer hub portion 66 and up an inclined lead to the end face of the hub, whereby said gear 67 is moved endwise inwardly against said member 64 and the dog 62 at the end of said member 64 engages between a pair of the peripheral teeth of said star wheel 61 and is thereby retained until the notch 71 again comes into position to receive the pin 68.

The gear 70 meshes circumferentially with and is movable longitudinally in relation to an idler pinion 72 which has a gear 73 fixed thereto and rotatable therewith, said gear 73 meshing with a pinion 74 which is fixed on the shaft 75 which carries the minute hand 76 of the clock. By this arrangement the gear 70 rotates at the same speed as a gear 77 fixed on a sleeve 77', which latter is rotatable on the shaft 75 and carries the hour hand 78.

To set the controlling mechanism for the timed release of the dog 62 from the star wheel 61 a setting shaft 79 is provided, said shaft having a knob 80 on its outer end portion outside the front wall of the case 15 and just below the regular clock dial 81, said shaft 79 having a ratchet 82 fixed on its inner end portion just inside of the rear plate 16. Said ratchet engages a pawl 83 located on the inner face of said plate 16 whereby the shaft 79 may be rotated only in one direction. Fixed on said shaft 79 to rotate with the ratchet 82 is a gear 84 which meshes with a similar gear 85 fixed on said hereinbefore mentioned shaft 69, and said shaft 69 has on its forward end portion a gear 86 which meshes with a gear 87 rotatable about a hub portion 88 of a collar 89, on which latter the dial 81 is secured at its central portion, preferably by the same screw elements or bolts 89' by which said hub portion 88 is at-

fached to a bracket frame 90 on the front frame plate 35.

Secured to the outer face of the gear 87, as by the screws 91 is a circular plate 92 which is located just behind the dial 81 and has an annular dial band 93 on its outer face at the periphery thereof, said band 93 being divided into twelve equal spaces, the division lines 94 thereof being respectively numbered "1" to "12" inclusive, and 10 indicating hours, and said spaces being subdivided and the division lines thereof being respectively marked to indicate quarter hours, that is to say, the several sub-dividing lines 95 are respectively marked "15", "30" and "45", meaning 15 minutes.

The annular dial portion 93 of said disc 92 is covered throughout its extent by the outer stationary dial 81 except for an upper portion of the latter in which a sector shaped opening 96 is provided (see Figures 1 and 5), said opening 96, as shown, being of a length sufficient to expose two adjacent hour numerals of said dial 93, and at the middle of said opening 96 is a substantially V-shaped frame 97, the apex 98 of which coincides with the uppermost division mark of the clock dial 81 indicating the hour "12". The set time reading of said dial 93 is through the V-shaped frame 97, that is to say, the disc 92 is turned until the particular character on the 20 annular dial 93 indicating the time set for releasing the switch gear actuating means for starting or stopping radio operation is brought into register with the opening of the V-shaped frame 97. For example, as shown in Figures 1 25 and 5, the time set is 30 minutes past 2 o'clock, the numeral "30" indicating minutes being exposed within said frame 97 and the numeral "2" indicating the hour being exposed in the opening to the left of said frame 97. By the same token 30 if the release of the switch gear actuating means is to occur on the hour, say 2 o'clock, the hour number "2" is set in the frame 97.

By turning the knob 80 the shaft 79 is correspondingly rotated, and through the train of gears just above described, the shaft 69 is rotated and the gear 86 thereon being in mesh with the gear 87 to which the dial plate 92 is attached, said plate 92 is thereby rotated until the number on the dial 93 indicating the time for which 35 switch gear 30 is to be operated is brought into register with the frame 97 at the middle of the opening 96 in the clock dial 81. During this actuation of the dial plate 92 the spring member 64 is held inwardly with its dog portion 62 in engagement with the star wheel 61 unless the gear 67 has been rotated to bring the notch 71 of the hub portion 66 into position to receive the pin 68 on the shaft 69 and permit the member 64 to swing outwardly and retract the dog 62 from said star 40 wheel 61, said gear 70 rotating in synchronism with the gear 77 which drives the hour hand, as hereinbefore described. Thus, in turning the shaft 69 after setting the dial plate 92, as just above described, the engagement of the pin 69 on said shaft 69 by the notched portion 71 of the hub 66 of said gear 67 occurs at the set time, and upon the release of the dog 62 from said star wheel 61 the train of gearing between the motor spring 55 and said switch gear 30 is unlocked, 45 whereupon said gear 30 is rotated until arrested either by the engagement of one of its spoke members 46 with the pivotal arm 39 of said lever element 36 or by engagement of one of its lugs 47 with the other arm 41 of said lever member 36, said lever member, of course, having been

selectively positioned by manipulation of the knob 49.

To manually release the dog 62 from the star wheel 61 in order to operate the switch gear 30 before the time set for its automatic operation as hereinabove described, the lever 36 is provided with a longitudinal plunger member 99 which is extended through the knob portion 49 and is provided on its outer end with a knob 100, the inner end portion of said plunger 99 being turned angularly, as at 101, and engaged in an arcuate slot 102 provided in a lug 103 at the upper end of a lever 104, which latter is pivotally mounted in a bracket 105 on the outer face of the frame plate 35, said lever 104 having a laterally off-set 15 lower end portion 106 which projects between the outer face of the plate 35 and the adjacent upper portion of said spring member 64 which carries the dog 62. This lever member 104 is normally pressed by a spring 107 which urges its upper portion outwardly and its lower portion inwardly with the off-set 106 in contact with the plate 35, in which position of the lever 104 the plunger element 99 is longitudinally movable outwardly on the lever 36 and said lever 36 is swingable on 20 its pivot 38 without interference because the angular extension 101 of said plunger 99 is free to oscillate in the arcuate slot 102 in the lug 103 of said lever 104. By this provision the lever 36 may be moved in either of its two positions for 25 arresting the switch gear 30 in its rotation, and in either position of said lever 36 the plunger element 99 may be moved inwardly by pressing the knob 100 and thereby rock the lever 104 and retract the dog 62 from the star wheel 61.

From the foregoing it will be seen that the lever 36 may be set to stop the switch gear 30 in either circuit-closing or circuit-breaking relation to the two terminal contact elements 23 and the operation of said switch gear 30 prior to such selective stopping of the gears rotation which is automatically accomplished at the desired time by accordingly setting the plate 92 to locate the proper number on the dial portion 93 in relation to the V-shaped frame 97 of the sight opening in 45 the clock dial 81. That is to say, the device of the present invention may be set so that the radio will automatically start at a certain time and remain in operative condition until it is turned off by hand, or by reversing the controlling lever 36 50 and starting the radio by hand after setting the dial plate 92 for the time desired to stop operation, it will continue to operate until such set time and the switch gear 30 is arrested by engagement of one of its lugs 47 with the arm 41 of 55 said lever 36 and the terminal members 23 are in contact with the opposite insulated portions 31 of said gear 30.

The regular clock mechanism will now be described. As shown, there is a reciprocating rack 60 bar 108 having a knob 109 at its outer end for its manipulation, said rack bar 108 being engageable with a gear 110 which carries a pawl 111 in engagement with a ratchet 112 fixed on a shaft 113 for winding a spring (not shown) in the barrel 65 114 and by which a gear 115 is rotated to drive a pinion 116 which drives the minute hand shaft 75 through a suitable friction clutch 116' between said pinion 116 and said shaft 75, which latter, as hereinbefore described, carries the minute hand 76 and through the medium of the sleeve 77' and the described train of gearing between said sleeve 77' and shaft 75, drives the hour hand 78, all as in the ordinary conventional 70 clock mechanism.

A conventional setting mechanism for the clock hands is illustrated in the drawings as comprising a knob 117 on a shaft 118, said knob 117 being located outside the front wall of the case 15 and just below the clock dial 81 in substantially the same plane as but to the left of the knob 80 of the setting mechanism for the operation and control of the switch gear 30. The shaft 118 is mounted to reciprocate endwise as well as rotate about its axis, and its rear end portion is extended beyond the rear plate 16 of the case 15, where it is provided with a washer 119 and a retaining cross-pin 120, said washer being engaged by an elongated leaf spring element 121 secured at its upper end to the plate 16, as at 122, and yieldably holding the shaft 118 in its normal retracted position as shown in Figures 2, 3 and 6. This shaft 118 has a gear 123 fixed thereon and in mesh with a flanged gear 124 which is mounted 20 on a shaft 125 longitudinally slidable in the rear frame plate 21 of the clock mechanism and the back plate 16 of the clock case, said shaft 125 having its outer end in abutting relation to the spring element 121, and a spring 126 being sleeved 25 on the inner end portion of said shaft 125 and interposed between the frame plate 21 and the front face of said gear 124. The gear 124 is normally located rearward of and out of mesh with a gear 127 fixed on the rear end portion of the 30 minute hand shaft 75 but is adapted to engage said gear 127 when the shaft 118 is pulled forwardly by grasping the knob 117 and thereby retracting the spring element 121, which latter, in turn, moves the engaged shaft 125 forwardly 35 and brings the gear 124 into mesh with said gear 127, over-travel of the gear 124 being prevented by the circumferential flange 124' of said gear 124 engaging the adjacent peripheral portion of said gear 127. With the gears thus engaged the 40 shaft 118 is rotated by the means of the knob 117 in either direction and the shaft 75 is accordingly rotated to effect the setting of the minute hand 76 and hour hand 78.

To limit the outward movement of the ratchet bars 52 and 108 which operate the respective winding gears 51 and 110, said bars are preferably provided at their inner ends with laterally projecting studs 128 which may come in contact with the ends of guide brackets 129 provided for 45 the rack bars on the rear frame plate 21 beneath said gears 51 and 110. Also, to resist the upward thrust of the lugs 47 of the switch gear 30 when said lugs come in contact with the pivotal arm 41 of the switch lever 36, the shelf 34 of the frame 50 plate 35 which supports the lever 36 is provided with a guiding and retaining clip 130 which overhangs said pivotal arm 41.

Obviously, the structure admits of considerable modification within the spirit and scope of the 60 invention, as defined by the appended claims. Therefore, the invention is not limited to the specific construction and arrangements shown in the accompanying drawings.

What is claimed is:

65 1. In a radio starting and stopping control, a clock mechanism including an ordinary time train and controlling means therefor, a switch gear driving train including a releasable latch device and means coordinated with the time train 70 and adapted to be set selectively for the release of said latch device automatically at a predetermined time, and circuit closing means for controlling the starting and stopping of operation of a radio, said means including a rotatable element having an annular contact surface portion

of electrical non-conductivity generally throughout, a series of contact spots of electrical conductivity at intervals throughout the circular extent of said non-electric surface contact portion, an electrical circuit terminal element in contact with said rotatable element, and manually operable means for stopping rotation of said rotatable element in relation to said terminal element. 5

2. In a radio clock, a switch including a gear having annularly arranged alternate conductive and non-conductive electrical portions on its opposite faces, a pair of circuit terminal elements engaging said gear on opposite sides thereof for contact with said electrical conductive and non-conductive portions of the gear, means for selectively stopping operation of said gear, said means including a lever having extensions of different length and said gear having different annularly arranged correlated lever engaging portions, a clock mechanism having a regular 20 time train, a normally locked switch gear operating train, and means cooperatively associated with said regular time train and said gear operating train whereby to selectively release the locking means for the gear operating train at a 25 predetermined time.

3. In a radio starting and stopping control, an electrical circuit switch including a pair of terminal contact members, a rotatable element located between said terminal members, said rotatable element having an annular surface on opposite sides of non-electric conductivity, a series of cross-connected electrical contact spots at intervals throughout said annular non-electric surfaces, stop members on said rotatable element respectively correlated to said electrical and non-electrical surface portions of the element, a manually operable on and off switch element having engaging portions movable alternately into and out of the path of said stop members of the rotatable element, a clock mechanism for actuating said rotatable circuit switch element, said clock mechanism including a releasable latch for the driving means thereof for said rotatable element, and means selectively set in coordination with the time train of the clock mechanism 30 for automatically releasing the latch of the driving means for said rotatable switch element. 35

4. In a radio starting and stopping control, an electrical circuit switch including a pair of terminal contact members, a rotatable element located between said terminal members, said rotatable element having an annular surface on opposite sides of non-electric conductivity, a series of cross-connected electrical contact spots 40 at intervals throughout said annular non-electric surfaces, stop members on said rotatable element respectively correlated to said electrical and non-electrical surface portions of the element, a manually operable on and off switch element having 45

engaging portions movable alternately into and out of the path of said stop members of the rotatable element, a clock mechanism for actuating said rotatable circuit switch element, said clock mechanism including a releasable latch for the driving means thereof for said rotatable element, means selectively set in coordination with the time train of the clock mechanism for automatically releasing the latch of the driving means for said rotatable switch element, and manually 50 operable means coordinated with said manually operable on and off switch element for releasing said latch. 55

5. In a clock mechanism for controlling the starting and stopping of radio operation, a cir- 70 75

cuit switch including a pair of cooperable terminal elements and an interposed switch gear provided on its opposite sides with alternate annular electrical and non-electrical contact portions successively engageable with said terminal elements, a driving train for said switch gear coordinated with the time train of the clock mechanism, a releasable locking device for said driving train, setting means for releasing said switch gear driving train at a pre-determined time, said means including a dial located in correlation to the regular clock dial, said latch release setting means dial being covered by the regular clock dial and having the set indicating portion exposed through an opening provided therefor in said regular clock dial, and a manually operable on and off switch lever for selectively stopping rotation of said switch gear in position with relation to said circuit terminal members to either open or close the circuit.

6. In a clock mechanism for controlling the starting and stopping of radio operation, a pair of circuit terminal members, an interposed rotatable switch gear having spokes connecting its hub and rim portions, and radial lugs extending inwardly from its rim portion and off-set laterally from the plane of the spokes of the gear, said gear having annular bands of non-electric conductivity on its opposite sides and cross-connecting studs of electrical conductivity and having their opposite end faces exposed through the surface of said annular non-electric bands, said studs being insulated from each other and from the gear body, a manually operable on and off switch having oppositely disposed arms one of which is movable into the path of the spokes of the switch gear, and the other into the path of said lug portions of the gear by the alternate operation of said on and off switch whereby to stop

the gear in relation to said circuit terminal members to open or close the circuit, at will, time controlled means coordinated with the regular clock time train for rotating said switch gear, and releasable locking means for the switch gear driving means having provision for the manual setting thereof and automatic release at the set time.

7. In a clock mechanism for controlling the starting and stopping of radio operation, a pair of circuit terminal members, an interposed rotatable switch gear having spokes connecting its hub and rim portions, and radial lugs extending inwardly from its rim portion and off-set laterally from the plane of the spokes of the gear, said gear having annular bands of non-electric conductivity on its opposite sides and cross-connecting studs of electrical conductivity and having their opposite end faces exposed through the surface of said annular non-electric bands, said studs being insulated from each other and from the gear body, a manually operable on and off switch having oppositely disposed arms one of which is movable into the path of the spokes of the switch gear, and the other into the path of said lug portions of the gear by the alternate operation of said on and off switch whereby to stop the gear in relation to said circuit terminal members to open or close the circuit, at will, time controlled means coordinated with the regular clock time train for rotating said switch gear, releasable locking means for the switch gear driving means having provision for the manual setting thereof and automatic release at the set time, and means associated with the on and off switch for manually releasing the driving means for said switch gear.

MARVIN D. YORK.
